(57) **CLAIM**

The ornamental design for a front bumper for a motor
vehicle, as shown and described.

DESCRIPTION

FIG. 1 is a perspective view of a front bumper for a motor
vehicle of our new design;

FIG. 2 is a front view of our new design;

FIG. 3 is a rear view of our new design;

FIG. 4 is a top view of our new design;

FIG. 5 is a bottom view of our new design;

FIG. 6 is a right-side view of our new design, the left-side
view being a mirror image thereof;

FIG. 7 is a cross-sectional view of our new design taken
along the line 7—7 in FIG. 2, showing the profile of that
portion of the design;

FIG. 8 is a cross-sectional view of our new design taken
along the line 8—8 in FIG. 2, showing the profile of that
portion of the design; and,

FIG. 9 is a cross-sectional view of our new design taken
along the line 9—9 in FIG. 2, showing the profile of that
portion of the design.

As used herein, right and left refer to the orientation of the
design depicted in the figures above, not the right and left
sides of the design when mounted on a motor vehicle.
